SWATCH COVER

Neil B. Powter, Senneville, Quebec, and John L. McCaul, Westmount, Quebec, Canada, assignors to Howard Smith Paper Mills Limited, Province of Quebec, Canada

Application March 7, 1938, Serial No. 194,356

5 Claims. (Cl. 206—82)

This invention relates to improvements in swatch exhibits; and it comprises a folder in which a swatch assembly is enclosed so that it may be conveniently carried about in the pocket without danger of injury thereto and may be conveniently exhibited when occasion requires, said folder comprising front and back leaves provided with complementary fastening means whereby they may be interlocked in either a swatch enclosing or a swatch exhibiting relation.

The invention also comprises a background or mounting member constructed so that the swatch may be readily attached thereto, for exhibition or filing purposes, by means of a tab formed by interlocking the folder leaves in their swatch exhibiting relation.

Other characteristic features and advantages of the invention will be apparent from the following detailed description taken in connection with the accompanying drawings, in which—

Fig. 1 is a front view of the swatch and folder assembly as it appears when the front and back leaves of the folder are interlocked in their swatch enclosing relation.

Fig. 2 is a rear view of the assembly appearing in Fig. 1.

Fig. 3 is a transverse sectional view taken along the line 3—3 of Fig. 2.

Fig. 4 is a front view of the swatch and folder assembly as it appears when the front and back leaves of the folder are interlocked in their swatch exhibiting relation.

Fig. 5 is a rear view of the construction appearing in Fig. 4.

Fig. 6 is a transverse sectional view taken along the line 6—6 of Fig. 4.

Fig. 7 is a perspective view of a background or mounting member provided in accordance with this invention.

Fig. 8 is a vertical sectional view showing the manner in which the swatch assembly is mounted on the background or mounting member by means of the tab formed by the front and back folder leaves when the latter are interlocked in their swatch exhibiting relation.

In these drawings we have shown a conventional swatch comprising paper samples 5 arranged, in the usual shingled relation, on a relatively stiff cardboard or other suitable backing 6. This swatch assembly is secured within a folder comprising a sheet of flexible cardboard or other suitable flexing material folded upon itself to provide front and back leaves 7 and 8 having their upper edges integrally joined by a portion 9

overlying the upper edge of the swatch assembly.

The lower portion of leaf 9 is shaped to provide a downwardly directed locking tongue 9a terminating at the lower edge of backing 6. The front leaf 7 is made longer than the swatch backing 6 to provide an extension 10 which is foldable, in the crease line 11, to a position overlying the lower portion of the back leaf 8. The extension 10 is retained in this folded position by passing the tongue 9a through the slot 12 as shown in Figs. 2 and 3.

The upper portion of the swatch assembly comprising sample sheets 5 and backing 6 may be secured in any suitable manner to the upper portions of the front and back folder leaves 7 and 8. In the present instance we have shown these parts secured together by staples 13 located a suitable distance below the upper edge of the folder. Leaf 7 is creased, below the staples 13, to provide transversely extending fold lines 15, 16 and 17. The intermediate line 16 is spaced below the upper line 15 a distance corresponding approximately to the distance between line 15 and the upper edge of the folder. The lower line 17 is spaced from the intermediate line 16 a distance corresponding approximately to the thickness of the swatch assembly plus the thicknesses of the front and back folder leaves 7 and 8.

When the front and back folder leaves 7 and 8 are interlocked, as shown in Figs. 1 to 3 inclusive, the swatch assembly is adequately protected and may be conveniently carried about in the pocket without danger of injury. When the swatch is to be exhibited, tongue 9a (Fig. 2) is withdrawn from slot 12 and the front folder cover 7 is folded along the fold lines 15, 16 and 17 to assume the position shown in Figs. 4, 5 and 6. Leaf 7 is then secured in this swatch exhibiting position by again passing tongue 9a through slot 12 as shown more particularly in Figs. 5 and 6.

For exhibition mounting or filing purposes it is sometimes desirable to provide a background or mounting member to which the swatch may be conveniently attached. To this end the present invention contemplates the provision of a background or mounting member of the type exemplified in Figs. 7 and 8. As here shown this member 18 consists of a sheet of dark colored cardboard or other suitable stiff material folded upon itself to provide front and back portions 19 and 20 which are secured together, at the edges opposite the fold line 21, by staples 22 or other suitable fastening means. The front member 19 is provided with a slot 23. When folder leaves 7 and 8 are interlocked as shown in Fig. 6, they form a

tab which, as shown in Fig. 8, may be passed through slot 23 into the space provided between the front and back portions 19 and 20 of the background or mounting member 18. When the 5 resulting assembly is used for display purposes the dark color of member 18 affords a desirable background against which the various sample sheets 5 may be effectively exhibited.

Having thus described our invention, what we 10 claim is:

1. A device of the character described comprising a pad of sample sheets arranged in shingled relation so that the lower edge of each sheet is spaced above the lower edge of the next upper sheet, front and back protecting leaves having their upper portions secured to the upper portion of the pad, said front leaf being extended to provide an extension capable of being folded over the lower edge of the pad to overlie the lower portion 15 of the rear leaf and means for securing said extension in such folded position, said device being further characterized in that the front leaf is creased, below its point of attachment to the upper portion of the pad, to permit said leaf to be folded over the upper edge of the pad to a pad exhibiting position in which the front leaf overlies the rear surface of the back leaf, the extension of the front leaf being, in this position of 20 said leaves, secured in place by the previously mentioned securing means.
2. A device of the character described, comprising a pad of sample sheets arranged in shingled relation so that the lower edge of each sheet is spaced above the corresponding edge of the 25 next upper sheet, a folder comprising front and back protecting leaves having their upper edges integrally joined together by a connecting portion overlying the upper edge of the pad and means fastening the upper portions of said front and back leaves to the upper portion of the pad,

said device being further characterized in that the front leaf is provided, below the portion attached to the pad, with upper, intermediate and lower transverse fold lines, the intermediate fold line being spaced from the upper fold line a distance corresponding closely to the distance between the upper fold line and the upper edge of the front leaf and said lower fold line being spaced from the intermediate fold line a distance corresponding closely to the thickness of the pad plus 10 the thickness of the front and back leaves. 5

3. A device as set forth in claim 2, in which the front leaf is made longer than the pad to provide an extension capable of being folded around the lower edge of the pad to overlie the lower portion 15 of the back leaf, and means for securing said extension in such folded position.

4. A device of the character described comprising a pad of sample sheets arranged in shingled relation so that the lower edge of each sheet is 20 spaced above the lower edge of the next lower sheet, front and back protecting leaves covering the front and back portions of said pad, means fastening the upper portion of the pad to the overlying upper portions of said leaves, said front 25 leaf being provided, below said fastening means, with transverse fold lines along which the front leaf may be folded to a sample exhibiting position in which the front leaf overlies the upper edge of the pad and the rear side of the back leaf, and 30 means for securing the front leaf in such folded position.

5. A device as set forth in claim 4, in which the front and back leaves are provided with interlocking parts for securing the front leaf in place 35 when the latter is folded to its pad exhibiting position.
